UNITED STATES PATENT OFFICE.

JULIUS JUDELSON, OF NEW YORK, N. Y.

DRIER.

Application filed April 18, 1921. Serial No. 462,324.

To all whom it may concern:

Be it known that JULIUS JUDELSON, citizen of the United States, and resident of the city of New York, in the county of Bronx 5 and State of New York, has invented certain new and useful Improvements in Driers, of which the following is a specification.

This invention relates to driers. More particularly this invention relates to driers 10 wherein the clothes or materials to be dried are held in a drying chamber where the moisture is evaporated therefrom.

One of the objects of this invention is to provide a drier of the character described 15 with efficient and practical means for holding the materials in the drying cabinet and for readily removing the materials therefrom.

Another object is to provide a drier of the 20 character described with a drying rack and supporting frame and guide therefor which shall be economical of floor and drier space.

A further object of this invention is to provide in a drier of the character described 25 a drying rack and frame for loading and unloading the materials to be dried which may be readily moved in and out of the drier cabinet and adapted to be totally located therin so as to afford a compact and neat 30 cabinet.

Other objects of this invention will in part be obvious and in part hereinafter pointed out.

Certain features herein shown and described are shown described and claimed in 35 my co-pending applications for Patent Serial Nos. 458,314 and 462,323, filed respectively in the United States Patent Office the 4th day of April, 1921, and on the 18th day of 40 April, 1921.

With the above exceptions the invention accordingly consists in the features of construction, combinations of elements and arrangement of parts which will be exemplified in the construction hereinafter described 45 and of which the scope of invention will be indicated in the following claims.

In the accompanying drawings in which is shown one of various possible illustrative 50 embodiments of this invention,

Fig. 1 is a perspective view of my improved drier, showing the rack carrying frame and one of the racks pulled out of the cabinet ready for loading of said rack 55 with material to be dried; and

Fig. 2 is a vertical section of my invention

taken through one of the racks vertical and horizontal central portions of the device being omitted in order to show the remainder on an enlarged scale.

Fig. 3 is a detail partial section of the heater chamber cut along line 3—3 of Fig. 2.

Referring in detail to the drawing, A indicates the drying cabinet comprising the side walls 10, rear walls 11 and the top 12. The rear walls 11 are made preferably of two independent sheets of metal 13 and 14 so as to enclose the air space 15 therebetween and suitably jointed to each other at the side edges thereof as at 16. The top 12 comprises 60 the sheets 22, 23 enclosing the air space 24 therebetween; and the side walls (not shown in detail) are of similar double-wall construction. For holding the sides 10 together and for maintaining the rear walls 11 in 65 close contact with said sides, suitable means such as the transversely disposed straps 29 are provided. The ends 40 of said straps are twisted at right angles to the body thereof and terminate in downward extending 70 hooks 41. On the inner faces of the side walls are attached the strap catches 42 adapted to receive the hooks 41.

Heat is supplied to the cabinet by means of a suitable heater 52 which may be arranged outside of said cabinet the heated air being conducted through a chamber 53 located near the bottom of the cabinet and having baffle plates 54 for retarding the heat vehicle in its passage through the chamber 80 before escaping through the flue 55.

For exhausting much of the moist air from the inside of the cabinet during the drying operation, a suitable vent box 56 having openings 57 on one side thereof is 90 interposed in said flue 55. A hinged door 58 may be arranged at the front of the cabinet for allowing access to the heating chamber 53.

The apparatus for loading and unloading 100 the materials into and out of the cabinet and holding the materials in place will now be described. The means employed for this purpose comprises a rack member having a door 43 at one end thereof, the member 44 105 at the other end thereof and horizontal cross bars 45 suitably connecting said door and said end member.

A frame 50 is adapted to support the front 110 end of said rack member, the horizontal guides 49 and 49' secured to the upper and lower ends of said frame respectively being

arranged to telescope into the drying cabinet in a manner hereinafter described. A trolley 46 is secured to the end member 44 of the rack while a similar trolley 47 is secured 5 to the outside of the door 43. Wheels such as 61 and 61' are secured to the trolleys 46 and 47 respectively and serve to suspend the rack from the horizontally disposed trolley guides 48 and 49 respectively. When the 10 door 43 is in closed position the strain is taken off the wheel 61' which is rigid with the plate 47' by the member 66 which has a wedge portion 67, which rests normally on the member 68 of the door frame. This 15 wedge portion 67 is cut away obliquely at the end to give a cam face 67a so that when the door is moved out the cam face rides over the member 68 and drops down, thus carrying the wheel 61' down with it into contact 20 with the guide 49.

For allowing the frame 50 to be moved from its outermost to its innermost position where it will be out of the way during the 25 drying operation and where it occupies an in- appreciable area of floor space, the guides 48 and 48' are made hollow to receive the guides 49 and 49' respectively. A bushing 63 is pro- 30 vided at the front end of each of said guides 48 and 48' while a wheel 64 is rotatably se- cured near the rear end of each of the guides 49 and 49' which are thereby constrained to move horizontally in and out of said guides 48 and 48'.

Castors such as 51 are suitably secured 35 to the lower end of said frame 50 as by means of the angle brackets 65, said castors resting on the floor and serving to take up the stress due to the weight of said frame and the racks supported thereby from the 40 guides 48 and 48' when said frame is in its outermost position.

By reason of the above described arrange- 45 ment, it will be seen that the frame 50 may be moved horizontally independently of the movement of the rack so that if desired, 50 said frame may be maintained in its outermost position at all times in which event only the rack is moved into the cabinet for drying the material placed thereon. How- 55 ever, it will be obvious that the frame 50 may also be moved readily inwardly out of the way, when desired after or simultaneously with the inward movement of said rack. It will be apparent that the rack and frame 60 may be moved in and out of the cabinet in one operation if desired by taking hold of the handle 69 and frame simultaneously.

The function and operation of the rack 65 and frame in connection with the drying cabinet will now be clear. The frame 50 is first pulled out from the inside of the cabinet, the rods 49 and 49' being withdrawn from the rods 48 and 48' respectively, the castors 51 rolling along the floor, while said frame is being moved. The rack may now be

readily withdrawn from the cabinet by pulling on the handle 69 whereby the trolley wheels 60 and 61 roll on the guides 48, 49 respectively until the end 44 is stopped by means of a suitable stop member 62 and the opening in the front end of the cabinet is sealed by said end 44. After the rack has been loaded with material to be dried, both said rack and the frame carrying it may be pushed back with the cabinet out of the way, 70 the drying operation beginning as soon as the heating apparatus is turned on. Heated air or some other such heat vehicle will then circulate through the chamber 53 and the heat transmitted to the space in the drying cabinet outside the heating chamber. The used heat vehicle then escapes through the vent 55 while the moisture from the cabinet is drawn out through the vent openings 57.

It will thus be seen that there is provided 85 apparatus in which the several objects of this invention are achieved and which is well adapted to meet the conditions of practical use.

As various possible embodiments might be 90 made of the above invention and as various changes might be made in the embodiment above set forth, it is to be understood that all matter herein set forth or shown in the accompanying drawings is to be interpreted 95 as illustrative and not in a limiting sense.

Having thus described my invention I claim as new and desire to secure by Letters Patent:—

1. In a drier, a cabinet having an opening 100 in one end thereof, a drying rack movable in and out of said cabinet, an end member on said rack for sealing said opening in the outermost position of said rack, and a frame for supporting said rack and movable in and 105 out of said cabinet independently of and together with said rack.

2. In a drier, a drying cabinet, a rack slid- 110 able in and out of said cabinet, means in said cabinet for supporting one end of said rack and a frame slidable relatively to said cabinet independently of said rack for sup- porting the other end of said rack.

3. In a drier, a cabinet, a rack adapted to slide in and out of said cabinet, means for supporting said rack comprising a trolley at each end of said rack, a hollow trolley guide in said cabinet on which the rearmost trolley is mounted, a rack-carrying frame and a rod for supporting the foremost of said trolleys 115 adapted to enter said trolley guide and se- cured to said frame.

4. In a drier, a cabinet having an opening in the front end thereof slidable in said cabinet and a rack comprising a rear mem- 125 ber adapted to seal said opening in the outermost position of said rack, a door adapted to seal said opening in the innermost position of said rack, rods extending between said rear member and said door, and means for 130

slidably supporting said rack in its innermost and in its outermost positions.

5. In a drier, a cabinet having an opening in the front end thereof, a rack slidable in and out of said cabinet comprising a rear member adapted to seal said opening in the outermost position of said rack, a door adapted to seal said opening in the innermost position of said rack, means for supporting material to be dried, extending between said rear member and said door, and means for supporting said rack comprising a trolley at each end of said rack, a hollow trolley guide in said cabinet for supporting the rearmost of said trolleys, a frame slid-
10 able in and out of said cabinet, and means secured to said frame for supporting the foremost of said trolleys and adapted to telescope into said hollow guide.
15 6. In a drier, a frame, a rack carried by said frame, and means for slidably support-
20

ing said rack from said frame comprising a hollow rod, a trolley on said rack carried by said rod, a rod secured to said frame adapted to telescope into said hollow rod, a second trolley on said rack carried by said second rod, and means for guiding the relative movement of said rods.

25 7. In a drier, a frame, a rack carried by said frame, and means for slidably supporting said rack from said frame comprising a hollow rod, a trolley on said rack carried by said rod, a rod secured to said frame adapted to telescope into said hollow rod, a second trolley on said rack carried by said second rod, and means including a bushing and pulley for guiding the relative movement of the guide rods.

30 Signed at New York city, in the county of New York and State of New York, this 14th day of April 1921.

35 JULIUS JUDELSON.
